UNITED STATES PATENT OFFICE.

RICHARD OWEN, OF LIVERPOOL, ENGLAND.

ADJUSTABLE BRACKET FOR SUPPORTING SHELVES OR THE LIKE.

1,089,863.

Specification of Letters Patent. Patented Mar. 10, 1914.

Application filed June 15, 1912. Serial No. 703,926.

To all whom it may concern:

Be it known that I, RICHARD OWEN, subject of the King of England, residing at 44 Brunswick road, Liverpool, in the county 5 of Lancaster, England, have invented new and useful Improvements in and Appertaining to Adjustable Brackets for Supporting Shelves or the like, of which the following is a specification.

10 The invention has for its object an improved bracket or shelf support adapted for use in confined situations and where security is required and which shall possess a high degree of efficiency for the purposes 15 intended, coupled with simplicity, low cost and ease of manipulation.

In order that the invention may be readily understood, an embodiment of the same is set forth in the accompanying drawing and 20 in the description based thereon. As, however, the invention is capable of embodiment in other varied structural forms, it is to be understood that the specification and drawing are to be taken in an illustrative 25 sense and not as unnecessarily limiting the invention.

In the drawing Figure 1 is a side elevation showing a portion of the standard with the bracket in position; Fig. 2 is a similar 30 view showing the bracket in a position to be detached for adjustment; and Fig. 3 is a plan view of the parts in the relation shown in the other figures.

Referring to the figures of the drawing in 35 detail, A represents the standards arranged one at each end of the shelving and at intermediate points as may be required by the load to be supported.

B is the bracket, having a plate C pivoted 40 thereto at D and offset from the general plane of the bracket a distance corresponding roughly to the thickness of the standard. Projecting laterally from the bracket in its 45 upper portion is a stud E which is adapted to enter any one of a vertical series of apertures F formed in the standard A. The lower portion of the bracket has an integral offset portion in the shape of a lip G which is in substantially the plane of the plate C 50 and in a plane parallel to that of the bracket.

In positioning the bracket, the stud E is entered in an aperture F at the height desired, the parts being in the position shown

in Fig. 2. The bracket is then allowed to swing downward until it reaches the position indicated in Fig. 1, the offset lip G lying on that side of the standard opposite the bracket and the plate is swung to a position where it also lies alongside the standard on the same side as the lip and opposite the 60 stud. Thus the stud is prevented from leaving its seat in the aperture and the bracket is fixed firmly in position.

To adjust the bracket, the plate C is swung upward on its pivot by means of its 65 fingerpiece and the bracket is also tilted as indicated in Fig. 2 until the lip G clears the front edge of the standard, whereupon the stud can be moved laterally out of the aperture and placed in another aperture, higher or 70 lower. Obviously the plate C can be formed integral with the bracket similarly to the lip G but in such case it would be necessary to swing the bracket much higher in order to effect a clearance of the front edge of the 75 standard.

I claim:

1. The combination with a standard having therein a vertical series of transverse apertures, of a bracket having a portion 80 adapted to lie alongside the standard and provided with a laterally projecting stud adapted to enter one of the apertures, said bracket having a laterally offset lip adapted to lie alongside the standard opposite the 85 bracket, and a similarly offset plate pivoted to the bracket and adapted to lie on the same side of the standard as the lip.

2. The combination with a standard having therein a vertical series of apertures, of 90 a bracket having an upper portion adapted to lie alongside the standard and provided with a laterally extending stud adapted to enter one of the apertures, said bracket having in its lower portion an offset lip adapted to lie on that side of the standard opposite the bracket, and a similarly offset plate pivoted to the bracket and adapted to lie on 95 that side of the standard opposite the stud.

In testimony whereof I have signed my 100 name to this specification in the presence of two subscribing witnesses.

RICHARD OWEN.
